(57) **CLAIM**

The ornamental design for an electronic book, as shown.

DESCRIPTION

FIG. 1 is a perspective view of an electronic book showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof showing the electronic book unfolded for use.

Broken lines shown in the drawings illustrate portions of the electronic book, and form no part of the claimed design.

1 Claim, 7 Drawing Sheets
